No. 780,807.

PATENTED JAN. 24, 1905.

J. McGRATH.

NON-SLIPPING ATTACHMENT FOR BOOTS OR SHOES.

APPLICATION FILED SEPT. 6, 1904.

Fig. 1.

UNITED STATES PATENT OFFICE.

JOHN McGRATH, OF EAST LONG MEADOW, MASSACHUSETTS.

NON-SLIPPING ATTACHMENT FOR BOOTS OR SHOES.

SPECIFICATION forming part of Letters Patent No. 780,807, dated January 24, 1905.

Application filed September 6, 1904. Serial No. 223,520.

To all whom it may concern:

Be it known that I, JOHN McGRATH, a citizen of the United States, residing at East Long Meadow, in the county of Hampden and State 5 of Massachusetts, have invented certain new and useful Improvements in Non-Slipping Attachments for Boots or Shoes; and I do hereby declare the following to be a full, clear, and exact description of the invention, such 10 as will enable others skilled in the art to which it appertains to make and use the same.

My invention relates to boot and shoe attachments, and more particularly to an attachment for the sole of the boot or shoe designed 15 to prevent slipping when walking upon ice or slippery pavements and the like; and my invention consists of certain novel features of combination and construction of parts, the preferred form whereof will be hereinafter set 20 forth, and pointed out in the claim.

The prime object of my invention, among others, is to provide an attachment of the character specified which will be found reliably efficient and which may be readily applied to use and disengaged from the boot or 25 shoe when further use is not required thereof.

A further object of my invention is to provide an attachment designed to meet the requirements above specified and which will 30 prove flexible in character and will therefore readily conform to all the movements of the foot incident to wearing the same.

Another object is to prevent undue strain being placed upon the sole of the foot and 35 also to enable the attachment to be readily taken off and sharpened if deemed desirable.

Other objects and advantages will be hereinafter made clearly apparent, reference being had to the accompanying drawings, which are 40 made a part of this application, and in which —

Figure 1 shows a side elevation of my invention complete as applied to use. Fig. 2 is a bottom plan view of my invention as applied to use upon a shoe or boot of the usual 45 or any preferred construction, while Fig. 3 shows a longitudinal central section of a shoe with my attachment applied thereon.

For convenience of reference to the various details of my invention and coöperating ac-

cessories numerals will be employed, the 50 same numeral applying to a similar part throughout the several views.

Referring to the numerals on the drawings, 1 designates a shoe of the usual or any preferred construction, the same being designed 55 to be representative of boots and shoes in general to which my ice-creeping attachment is secured by means of the ankle-strap 2, supplemented by the toe-strap 3 or the equivalent thereof. The heel member 4 is provided with 60 a flange 5 to fit around or receive the heel of the boot or shoe, said flange having openings or slots 6, in which are anchored the ankle-straps 2, said straps being provided with a disengaging 65 buckle or clamp-like member 7 or the equivalent thereof. The heel member 4 is formed upon its forward side with a preferably integral extension 8, to the end of which is attached or may be integrally formed thereon the cross-bar 9 of a width to reach across the sole of the 70 shoe or boot. I have also provided a toe-plate 10 and intermediate bars or plates 11, 12, 13, and 14, it being understood that any desired number of said bars may be employed, as will be obviously necessary to cover the entire sole 75 of the shoe or boot, the said bars being flexibly connected together by means of the coiled wires or spring-like members 15. The spring-like members 15 may be connected at intervals 80 throughout their entire length with said cross-bars, whereby said bars will all be joined together and the last spring member joined to the bar 9 and the toe-plate 10; but in the present instance I have shown said spring members attached only at their ends, as designated 85

by the numeral 16, the end of the wire being interlaced through the aperture 16, provided in the contiguous edge of the bars or the toe-plate 10, as will be obvious. The spring-like members 15 will thus impart a high degree of 90 flexibility to the entire attachment, it being understood that each of the cross-bars mentioned, as well as the heel and toe plate, are provided with a plurality of teeth 17, preferably struck downward out of material of 95 said parts or otherwise attached in place, as desired. The plurality of teeth 17 are for the obvious purpose of preventing the foot

from slipping in any direction, and thereby affording a secure footing to the person wearing my attachment.

It will be understood that the spring members 15 are connected to the several cross-bars and the toe-plate in such a manner that the tension of the spring will hold the toe-plate firmly in place, and therefore prevent it from hanging down and coming in the way.

10 The entire attachment may be quickly removed from the shoe or boot, as by disengaging the buckles 7 and 18 or other equivalent fastening.

Obviously the various parts of my invention, excepting the spring-like members 15, may be readily fashioned from suitable sheet metal, the friction-points 17 being also formed at the same operation, and while I have described the preferred combination and construction of parts I desire to comprehend in this application all substantial equivalents and substitutes that may be considered as falling fairly within the scope and purview of my invention.

25 Having thus fully described my invention,

what I claim as new, and desire to secure by Letters Patent, is—

The herein-described ice-creeper or non-slipping attachment for boots and shoes, comprising a heel member shaped to fit the heel 30 and provided with frictional points to take into the ice, sleet and the like, said heel member having a forward extension 8 provided with a cross-bar 9; a toe-plate and a plurality of flexibly-united cross-bars joining the member 9 and toe-plate together, all of said parts being provided with a plurality of frictional devices or pointed extensions adapted to take into the ice, sleet &c. whereby the foot will be held against casually slipping in any direction, all combined substantially as specified and for the purpose set forth.

40 In testimony whereof I have signed my name to this specification in the presence of two subscribing witnesses.

JOHN McGRATH.

Witnesses:

HENRY D. MARSH,
MYRON HILLS.
